UNITED STATES PATENT OFFICE

ANDREW F. SMITH, OF SEATTLE, WASHINGTON

COMPRESSED-SPRING MACHINE

Application filed October 23, 1928. Serial No. 314,526.

The invention is a machine for making springs which is adaptable to compress the spring after it is wound and hold it while upon a mandrel which may be removed from the machine so that a casing may be placed over it to hold the spring in the compressed state before it is released by the holding means of the mandrel.

The object of the invention is to provide a machine for making springs which is adaptable to hold the spring in a compressed position until a cover which is adaptable to hold it in the compressed position is placed over it.

Another object of the invention is to provide a machine for making springs in which the spring material is evenly fed to the mandrel of the machine.

Another object of the invention is to provide means within a mandrel for compressing a spring from both ends while the spring is on the mandrel.

A further object of the invention is to provide a mandrel for a spring winding machine which may readily be removed.

And a still further object of the invention is to provide a spring winding machine which is of a simple and economical construction.

With these ends in view the invention embodies a mandrel, rollers positioned below the mandrel and on each side of the center, meshing gears at the ends of the mandrel and rollers, a feeding device, means for moving the feeding device, and means in the mandrel for compressing and holding a spring thereon.

Other features and advantages of the invention will appear from the following description taken in connection with the drawings, wherein:

Figure 1 is a side elevation of the machine with parts broken away;

Figure 2 is a cross-section through the mandrel and rollers on line 2-2 of Figure 1;

Figure 3 is a detail showing the mandrel removed from the machine and a canvas covering placed over the spring;

Figure 4 is an end elevation showing the arrangement of the operating gears;

Figure 5 is a detail showing the removable tips on the ends of one of the clamping members; and

Figure 6 is a detail showing the removable socket at the ends of the mandrel.

In the drawings the device is shown as it would be made, wherein numeral 1 indicates the mandrel, numeral 2 the base, and numeral 3 a spring that may be made upon the mandrel.

The mandrel 1 is made of a cylindrical shaped piece of material with slots 4 and 5 in its outer surface and adjacent the ends, and each end is provided with a tongue 6 as shown in Figure 6 which extends into a groove 7 in a member 8. The member 8 is mounted in a bearing member 9 which is held in the end members 10 and 11 of the frame, and it will be observed that the upper portion of the bearing 9 is omitted from the inner end 12 thereof to the point 13 as shown in Figure 6. This open portion extends from the top downward to the point 14 as shown in Figure 2 so that when the mandrel is in the position with the larger end of the tongue 6 upward it may be removed from the top of the machine, however, when the larger end of the tongue is downward or toward either side the wall of the bearing 9 will hold the tongue in place. It will also be observed that the tongue 6 and the slot 7 are tapered as indicated by the dotted lines shown in Figure 2. The bearings 9 are located at each end of the machine so that the mandrel is rotatably held at each end and although this type of bearing is shown it is understood that a bearing of any other suitable type may be used.

In the center of the mandrel is a shaft 15 having right-hand threads as indicated by the numeral 16 adjacent one end and left-hand threads as indicated by the numeral 17 adjacent the other end and on these threads are cross members 18 and 19. The ends of these members extend through the slots 4 and 5 in the mandrel as shown in Figure 1 and it will be observed that the member 18 is provided with a hook 20 which

holds one end of the spring and the ends of the member which are indicated by the numeral 21 are removable from the member 19 so that after the spring has been compressed and a holding cover placed over it the members 21 may be removed so that the spring may be removed from the end of the mandrel with the mandrel out of the machine. The members 21 may be held in the member 19 by any suitable means, however, in the design shown they are provided with tapered circular portions 22 that are held in sockets 23 as shown in Figures 2 and 5. It will therefore be observed that these members may readily be placed through the slots 5 with the members 22 placed in the sockets 23 and the compression of the spring against the surface 24 will wedge the members 22 into the sockets and rigidly hold them in place. One end of the rod 15 is journaled within the end of the mandrel as indicated by the numeral 25 and the opposite end which is also journaled in the mandrel extends beyond the end of the mandrel as indicated by the numeral 26. A crank 27 may be placed upon the end 26 of the rod 15 and in the design shown the end of the rod is squared and the crank is provided with a square hole so that the rod may readily be turned by the crank. The inner surface of the hub of the crank is also provided with teeth 28 which are adaptable to engage similar teeth 29 on the outer face of the member 8 so that the crank may be moved inward until the teeth engage when it is desired to rotate the mandrel. It is also understood that the mandrel may be rotated by any other suitable means and a motor or a pulley may be provided. The member 8 at the end of the mandrel is also provided with a gear 30 which meshes with gears 31 and 32 upon rollers 33 and 34 which are rotatably mounted in the end members 10 and 11 of the frame and it will be observed that as the mandrel is rotated the gears will rotate the lower rollers.

A feeding device 35 having a threaded hub 36 is mounted upon a threaded rod 37 so that as the rod is rotated the member 35 will move from one end to the other of the machine, and it will be observed that the member 35 is provided with an opening 37' through which the spring wire may be fed and the lower end of the member is provided with an opening 38 that is slidable on a bar 39. The screw 37 is rotatably mounted in the end members 10 and 11 and one end of the screw is provided with a gear 40 which meshes with the gear 30 as shown in Figure 4 which will rotate the screw 37 and move the member 35 to feed the spring wire.

It will be understood that other changes may be made in the construction without departing from the spirit of the invention, one of which changes may be in the general de-

sign or arrangement of the machine, another may be in the use of other means for removably holding the mandrel in the machine, another may be in the use of other means for holding the spring upon the mandrel, another may be in the use of other means for feeding the spring to the mandrel, and still another may be in the use of other means for operating the machine.

The construction will be readily understood from the foregoing description. To use the device the machine may be assembled as shown and the end of the wire held in the member 20. The mandrel may then be rotated by the crank or any other suitable means and as it is rotated the spring material will be fed through the member 35 to the mandrel and when a spring of a suitable length has been formed the crank 27 will be moved backward so that it will only rotate the rod 15 and as it is turned the members 18 and 19 will move toward each other and compress and hold the spring. The mandrel may then be rotated until the large end of the tongue 6 is at the top so that it may readily be removed. A canvas covering may then be placed over the spring as indicated by the numeral 41 and the canvas may be sewed and held by a wire or cord as indicated by the numeral 42. When this covering is secured to the spring the rod 15 may then be rotated so that the members 18 and 19 will move away from the ends of the spring and then the members 21 may be removed from the member 19 so that the spring may be removed from the end of the mandrel. It will therefore be observed that the device may be used for making a spring and also holding it until a covering is placed over it to hold it in the compressed state before it is removed from the mandrel of the machine.

Having thus fully described the invention what I claim as new and desire to secure by Letters Patent, is:

1. In a spring-winding machine of the class described, a frame, a removable mandrel in the said frame, means in the said mandrel for gripping and holding the ends of a spring that may be wound thereon, means for releasing the said spring-holding means, rollers cooperating with the said mandrel to form the spring, a suitable feeding device for feeding the spring material to the mandrel, and suitable means for rotating the said mandrel, rollers and feeding device.

2. In a device of the class described, a mandrel, clamping members projecting from the sides of the said mandrel, and means within the said mandrel for moving the said clamping members toward or away from each other.

3. In a device of the character described, a mandrel, means projecting from the sides

of the said mandrel for holding the ends of a spring that may be wound thereon, means within the mandrel for moving the said holding members backward or forward, and means for removing the tips from one of the said holding members.

4. In a device of the class described, a suitable frame, a mandrel rotatably supported within the said frame, means for holding the ends of the mandrel whereby it may be readily removed, holding members projecting through slots in the said mandrel, means for moving the said holding members toward or away from each other, suitable rollers cooperating with the said mandrel, and means for rotating the said mandrel and rollers.

In testimony whereof I affix my signature.
ANDREW F. SMITH.
